UNITED STATES PATENT OFFICE.

EDWARD E. PALMER, OF WOOSTER, OHIO.

SHADE AND CURTAIN FIXTURE.

No. 877,591.

Specification of Letters Patent.

Patented Jan. 28, 1908.

Application filed March 16, 1907. Serial No. 362,669.

To all whom it may concern:

Be it known that I, EDWARD E. PALMER, a citizen of the United States, residing at Wooster, in the county of Wayne and State of Ohio, have invented certain new and useful Improvements in Shade and Curtain Fixtures, of which the following is a specification.

My invention relates to improvements in shade and curtain fixtures designed for use in connection with windows and similar places where it is desired to attach and suspend window shades and curtains or draperies.

15. The invention relates more particularly to that class of shade and curtain fixtures in which the curtain-pole bracket is secured to the shade-roll bracket; and in my invention the shade-roll bracket is adjustably-attached 20 to the side of the window frame by an improved fastening-device requiring the use of but one screw.

The primary object of the invention is to produce a generally-improved device of this 25 class which will be exceedingly simple in construction, cheap of manufacture, efficient in use, and much better adapted to its intended purposes than any other device of the same class with which I am acquainted.

30. Another object of the invention is to provide a generally-improved attaching device adjustably-supporting both the shade-roll and curtain-pole bracket, and which may be easily attached to or removed from the 35 sides of any ordinary window-frame. A single screw is required for each attaching-device and this screw also performs the additional function of clamping the shade-roll bracket in any position to which it may be 40 moved horizontally to conform to shade-rolls and curtain-poles of varying lengths.

With these and other ends in view, the invention consists in the novel construction, arrangement and combination of parts, herein-after described, illustrated in the accompanying drawings, and particularly pointed out in the appended claims.

Referring to the drawings, forming a part 50 of this specification, Figure 1, is a top-plan view of the improved shade and curtain fixture attached to the sides of an ordinary window-frame and supporting an ordinary shade-roll and wooden curtain-pole. Fig. 2, a perspective view of the shade-roll bracket 55 and attaching and clamping device. Fig. 3, an end view of the improved fixture, the

curtain-pole bracket supporting an ordinary brass tubular telescoping curtain-pole or rod. Fig. 4, a plan view of the stamped blank for the attaching device before being 60 formed up. Fig. 5, a similar view of the shade-roll bracket.

Similar characters of reference designate like parts throughout all the figures of the drawings.

65 The shade-roll bracket of the improved fixture is made up of a single blank of sheet metal, as shown in Fig. 5, and is bent to form a main supporting-plate 1, and an outwardly-extending L-shaped shank portion 70 2, terminating in a bracket-head 3, provided with the usual openings 4, for taking over the end pins of the shade-roll 5. The shank portion 2, is provided with laterally-extending T-shaped wings 6, as shown most clearly 75 in Fig. 5, which wings are bent at right angles to the main body portion of the shank 2, and at the rear of the off-set portion 2^a, thereof, as shown most clearly in Fig. 2, forming guide-sockets or recesses 7, at the upper 80 and lower edges of the shank for the reception of vertically-arranged guide-shanks or pins of the curtain-pole brackets to be hereinafter described.

85 The main supporting-plate 1, is provided with a longitudinally-extending guide-slot 8, and at the outer end of this slot and at the rear of the shank portion 2, an opening 9, and guide-recesses 10, are formed to receive and take over the head 11, of the attaching 90 and clamping-screw 12, and upper and lower edges 13, of the attaching-plate or block 14. The upper and lower edges 13, extend along the front of the supporting-plate, and the guide-recesses 15, at the rear of the attaching- 95 plate (see Fig. 4,) form ways for the reception of the edges of the supporting-plate along the guide-slot 8.

100 The tang-heads 16, are adapted to impinge against the faces of the window-frame when the attaching-tangs 17, have been driven home by tapping upon the plate or block 14.

105 The fixture is preferably attached by inserting the attaching device in the guide-slot 8, through the opening 9, and recesses 10, and then driving the tangs 17, of the plate 14, into the window-frame; then adjust the shade-roll bracket longitudinally to the position desired; and then, finally, drive 110 the single attaching and clamping-screw 12, into the window-frame through the screw-

opening 18, until the impinging screw-head 11, has firmly clamped the supporting-plate 1, in position by the drawing down or clamping movement of the plate 14.

5. The curtain-pole bracket comprises an upwardly-extending shank portion 19, and outwardly-extending hook or bracket portion 20, having a recess 21, to form a seat for the reception of an ordinary wooden curtain-pole as shown in Fig. 1. The upper end of the hook portion 20, terminates in an upwardly-extending shank portion 22, for taking through transverse openings of an ordinary brass tubular telescoping curtain-rod 15 or pole 23, as shown in Fig. 3, when it is desired to use a curtain-pole of this style.

20 The base of the curtain-pole bracket terminates, in the present instance, in a pair of guide-shanks or pins 24, adapted to be seated within guide-sockets or recesses 7, formed by the laterally-extending wings 6, at the upper and lower edges of the shank 2, of the shade-roll bracket.

25 From the foregoing description, taken in connection with the accompanying drawings, the operation and advantages of my invention will be readily understood.

I have entered into a somewhat detailed description of the present and preferred embodiment of my invention in order to impart a definite understanding of the same. I do not desire, however, to be understood as restricting myself to the exact construction shown and described, as various changes 35 or modifications may be made in the form, size, and minor details of construction without departing from the principles or sacrificing any of the advantages of this invention.

What I claim and desire to secure by Letters Patent, is—

40 1. A shade and curtain fixture, comprising a main supporting-plate provided with a longitudinal slot, an outwardly-extending L-shaped shank formed integral therewith and terminating in a bracket-head, an attaching plate provided with headed tangs and ways or recesses taking over the edges of said slot, laterally-extending guide-wings formed integral with said shank, and a curtain-pole bracket mounted in said guide-wings.

45 2. In a shade-fixture, the combination with a shade-roll bracket provided with a supporting-plate having a longitudinal slot therein; of an attaching-plate provided with ways taking over the edges of said supporting-plate along said slot and tangs terminating in heads at the rear of said ways.

50 3. In a shade-fixture, the combination

with a shade-roll bracket provided with a shank having an opening and guide-recesses 60 at its rear, and a supporting-plate having a longitudinal slot terminating in said opening and recesses; of an attaching-plate provided with recess-ways for the edges of said supporting-plate along said slot and tangs terminating in heads at the rear of said recess-ways, and an attaching and clamping-screw mounted in an opening in said attaching-plate and extending through said slot.

55 4. In a shade and curtain fixture, the combination with a shade-roll bracket having an L-shaped shank provided with inwardly extending guide-wings at its upper and lower edges; of a curtain-pole bracket having guide-shanks at its lower end mounted in said guide-wings.

60 5. In a shade and curtain fixture, the combination with a shade-roll bracket having a shank provided with laterally-extending T-shaped wings forming guide-recesses at its upper and lower edges; of a curtain-pole bracket having its lower end mounted in said guide-recesses.

65 6. A shade and curtain fixture, comprising a main supporting-plate provided with a longitudinal slot, an outwardly-extending L-shaped shank formed integral therewith and terminating in a bracket-head, an attaching-plate provided with tangs and ways or recesses taking over the edges of said supporting-plate along said slot, a clamping-screw mounted in said attaching-plate and passing through said slot, laterally-extending T-shaped wings formed integral with said shank and forming guide-sockets adjacent thereto, 95 and a curtain-pole bracket terminating at its lower end in guide-shanks mounted in said guide-sockets.

7. A shade and curtain fixture, comprising a main supporting-plate provided with a longitudinal slot, an outwardly-extending L-shaped shank terminating in a bracket-head, an attaching-plate provided with recess-ways for the edges of said supporting-plate along said slot and tangs terminating in heads at the rear of said recess-ways, laterally-extending socket guide-wings formed integral with said shank, and a curtain-pole bracket mounted in said socket guide-wings.

100 In testimony whereof I have signed my name to this specification in the presence of two subscribing witnesses.

EDWARD E. PALMER.
